UNITED STATES PATENT OFFICE.

SYDNEY E. TAFT, OF FRAMINGHAM, MASSACHUSETTS, ASSIGNOR TO HEMPHILL COMPANY, OF CENTRAL FALLS, RHODE ISLAND, A CORPORATION OF MASSACHUSETTS.

KNITTING MECHANISM.

Application filed February 18, 1920. Serial No. 359,646.

To all whom it may concern:

Be it known that I, SYDNEY E. TAFT, a citizen of the United States, and a resident of Framingham, in the county of Middlesex and State of Massachusetts, have invented an Improvement in Knitting Mechanisms, of which the following description, in connection with the accompanying drawings, is a specification, like characters on the drawings representing like parts.

This invention relates to knitting machines and more particularly to knitting machines employing a series of knitting instruments each having independently movable loop forming elements and the principal object of the invention is to provide means to position and function said elements for narrowing and widening or fashioning.

20 The invention consists in the combination and arrangement of parts set forth in the following specification and particularly pointed out in the claims.

In the accompanying drawings I have shown merely for the purpose of illustration one type of a machine embodying the principles of my invention wherein:

Fig. 1 is a front elevation of the machine; Fig. 2 is a development in diagrammatic form of the various cams employed for functioning the knitting instrument and in relatively moving the members composing said instrument during the loop forming operations and also preparatory to operations of said members for narrowing and widening;

Fig. 3 is a detail front view of the instep cams and their supporting stand;

Fig. 4 is a vertical detail section on line 4—4 Fig. 3 illustrating the cams employed in moving the members of the knitting instrument to their idle or inoperative positions and for restoring said members to their operative positions;

45 Fig. 5 is a side elevation of one of the knitting instruments greatly enlarged.

For convenience in illustration I have shown the present invention adapted to a circular knitting machine wherein the needle cylinder revolves while the cam cylinder remains stationary during the knitting operation and the particular type of machine employed for this purpose is that commonly known as the Banner machine disclosed in the Patent No. 933,443 granted

to J. D. Hemphill, September 7, 1909, to which reference may be had. It is however distinctly to be understood that the invention is not limited to the type of machine shown but may be applied to any of the well known types either circular or straight knitting machines or to machines wherein the knitting cams and those associated therewith are revolved while the needle cylinder remains stationary.

Furthermore the machine described herein is for knitting hosiery wherein the heel and toe pockets are produced by narrowing and widening operations, but notwithstanding such a disclosure the invention is clearly applicable to machines adapted for knitting other articles of manufacture such as gloves, mittens and the like wherein the portions thereof are fashioned by narrowing and widening.

Inasmuch as certain general parts of the mechanism herein shown may be and preferably are the same as those shown in said Hemphill patent I have designated such parts by the same reference characters as are employed in that patent. Thus the machine frame is marked *a*, the rotary needle cylinder is marked *N*, the non-rotatable cam carrier *H* and the annular portion or ledge of said cam carrier is marked *M*.

The needle cylinder *N* is rotatably mounted upon a flat table *a* constituting the top of the frame *a* and receives its motion through suitable mechanism characteristic of said Banner machine. The main shaft *s* is journaled to rotate in said frame *a* and has thereon pulleys *p*, *p'* and *p''* indicating respectively the quick speed, slow speed and loose pulleys thereof from which the various parts of the machine derive the particular speed required to perform their respective functions.

The pattern shaft is indicated in Fig. 1 at *s'* and has mounted thereon pattern or cam drums *f* and *g*; *f'* is the pattern ring on the drum *f* which engages the member *b'* carried by the clutch shifting lever *b* which lever is employed in the usual manner for the purpose of controlling the shifting of the clutch *b* when it is desired to change the motion of the machine from rotary to reciprocatory or vice versa.

The details of the mechanism controlled by the pattern ring *f'*, through which the needle cylinder is reciprocated forward and

backward for flat or reciprocating knitting, may be and in the present example are the same as in said Hemphill Patent 933,443, and are unnecessary to be more fully shown herein.

The needle cylinder is provided with a series of knitting instruments 1 herein embodying in their construction relatively or independently movable loop forming elements consisting of a yarn drawing element 2 and a sheath or quill 3 preferably, though not essentially, of the type disclosed in my Patent 1,398,813, granted November 29, 1921 and, as shown most clearly in Figs. 2 and 4 thereof. The yarn drawing element 2 has a hook 4 wherewith to seize the yarn and draw the same through the old loop supported as in the usual manner of knitting by the knitting instrument while the sheath or quill 3 includes a loop penetrating or entering member 5 herein comprising a point 6 arranged at the back of the yarn drawing element and adapted to move in a groove 6' provided therein. Furthermore said loop entering member is connected herein along one side of the yarn drawing element by means of an inclined wall 5' (see Fig. 5) with a hump 7 disposed at the front edge of the sheath, which during certain periods in the loop forming operation, engages the old loop supported by the shank of the needle and separates the same from the new yarn that is being fed to the hook by the usual yarn feeding instrumentalities shown at 8, Fig. 1 and which instrumentalities mainly embody the principal features of the yarn feeding means of said Banner machine and therefore require no further description, said hump 7 also constituting a guard for the point of the hooked member to effect the shedding of said loop by said hooked member.

As previously stated the elements of said knitting instrument are independently movable, that is means are provided for imparting to the yarn drawing element movements herein entirely independent of that imparted to the sheath elements and the means for accomplishing this result herein consist of suitable cams which will now be described.

The yarn drawing elements 2 are each provided with butts some of which may be long as shown at 10 while others may be short as shown most clearly at 11 in Fig. 2 and when the machine is equipped to knit hosiery as in the present example the butts of the knitting instruments will be half long and half short, the long butts being arranged in one series and the short butts in a separate series. The sheaths 3 are similarly provided with long and short knitting butts 12 and 13 respectively and these butts are functioned in the manner hereinafter described. The long and short knitting butts

10 and 11 of the yarn drawing elements are all functioned by the knitting cams 14 during rotary knitting and during portions of reciprocating knitting, but as is customary at certain stages in the knitting operations as for example when producing narrowing and widening, one series of said knitting instruments are moved out of action so that the butts thereof will not engage the knitting cams and will thereby remain idle during such operations. It is for this reason, therefore, that half of the butts of said knitting instruments, as for example the butts 10 are made longer than the butts 11 so that the needles which are to be rendered inoperative may be engaged by certain instruments and moved to their inoperative positions without producing any interruption in the knitting by said short butt instruments. The means for effecting this result herein consists of cams similar to the usual instep cams of the Banner machine referred to, said cams being indicated at 15 and 16. The cam 15 is as usual arranged outside of the cam cylinder M and is therefore capable of engaging only that portion of the long butts 10 which extends beyond the short butts 11 and when said cam 15 is in a certain position, that is in the position shown in full lines Fig. 2, said long butts will then be engaged thereby and raised to the positions shown at A Fig. 2 or the idle level thereof. The cam 16 is similar to the usual needle restoring cam employed in stocking machines of the character described and is arranged to engage all butts and is mounted together with the cam 15 upon a suitable slide 18, (see Fig. 3) supported in a bracket or stand 19 in turn mounted upon the cam plate H so as to move with said plate during any vertical movement thereof to vary the length of the stitches in fashioning, or preparatory to transfer, the operation of said cam plate being a feature of said Hemphill Patent 933,443 and being fully described therein, no further description thereof is believed herein necessary.

The cams 15 and 16 are capable of being raised or lowered the distance necessary to throw out of action or into action the long butt yarn drawing members and means are employed for moving said cams at selected stages in the knitting operation whereby they will be positioned to perform the functions stated and in the present example I have shown for accomplishing these results a lever 20 herein consisting of a bell crank lever pivoted at 21 to a portion of the bracket or stand 19 as shown most clearly in Fig. 1. This lever 20 has an arm 22 pivotally connected at 23 with the slide 18. The other arm 24 of said lever extends downwardly through the cam plate H and is connected herein by means of a screw 25 with a link 26 having connection at its op-

posite end with the upper end of the clutch shifting lever b' thus insuring the shifting of cams 15 and 16 at the selected periods in the knitting operation, namely the periods 5 when the clutch is shifted from rotary to reciprocatory or vice versa.

The knitting cams for functioning the yarn drawing elements of the knitting instruments may be and in the present example are shown as substantially similar to the knitting cams of said Banner machine and include an upper central guide member e^2 and a lower central guide cam e^3 having a space therebetween sufficient to permit passage of the butts of all of the instruments, and in addition to said cams e^2 and e^3 are the right and left wedge-shaped knitting cams x , x' usually termed raise and draw cams. The cams x , x' perform substantially the same functions that the cams x , x' of said patent perform but these cams x are pivotally mounted at x^4 so that the upper ends will be depressed as the upper surfaces x' thereof are engaged by the butts of the 15 knitting instrument passing along the top of the cam M. These cams are, however, spring actuated so that upon the passing of said butts from the upper surfaces thereof, said cams will immediately return to their 20 upper full line positions as shown in Fig. 2. The purpose of pivoting said cams x as described is to allow the butts of the knitting instruments to pass in a substantially straight line from the top of the cam M 25 to the point where said butts are raised by reason of the engagement of the sheath butts thereof with the cam surface 30 as shown by the dotted lines in said figure, at which time the sheath element is 35 caused to penetrate and spread the loop.

The under surfaces of the cams x which are indicated at x^2 are utilized to draw the instruments whose butts engage said surfaces downwardly to effect the casting off 40 of the loops therefrom and the formation of the new stitches. The knitting instruments, after passing under said cams x engage the inclined cam surfaces x^3 of the annular cam M and cause said instruments to be deflected 45 to the top thereof. These cams cooperate with the stitch cams to produce the usual wave-like movements at the knitting points of said instruments when the knitting cylinder N is reciprocating in either direction. 50 The cams at one side only of said set will be employed during rotary knitting to produce such a wave-like movement of said knitting instruments.

There are times, as I have previously 55 inferred, when it is desirable to function substantially all of the yarn drawing elements during reciprocating knitting as, for example, when portions of the fabric are being fashioned and the web is being made 60 in an oppositely selvaged strip rather than

as a tubular web. However in the ordinary stocking machine only the short butt yarn drawing instruments are functioned by said knitting cams in reciprocating knitting, the long butt instruments being, at such times, 70 raised to their idle or inoperative level as indicated at A, Fig. 2 and when said short butt needles are being operated reciprocatingly the narrowing or widening operations 75 are generally being performed.

In general practice and in the present example immediately upon the raising of the instep or long butt elements to their idle level the narrowing process is instituted automatically and in the following manner: 80

Pivotaly mounted upon the usual cam block D which carries the main knitting or needle operating cams above described are two narrowing pickers R pivoted respectively adjacent the stitch cams x , x' and being in the present example substantial counterparts of the narrowing pickers disclosed in said Hemphill Patent 933,443 no further description thereof is believed necessary except to say that the ends of the arms of said pickers are provided with the usual ledges r' (see Fig. 2) and are positioned against the surfaces x' of said stitch cams so as to be engaged by the first short butt 90 of the series 11 during alternate reciprocations of the series, this being the usual manner of operation of said narrowing pickers and results in the picking of successive butts at opposite ends of the series from the active level to the upper or idle level A during said narrowing operations until the desired number of needles have been withdrawn from action but retaining their loops. At certain stages of the narrowing operations means are provided for instituting the restoration of said withdrawn needles to effect the widening operations of the fabric particularly in the formation of heel and toe 100 pockets and to accomplish this result, widening pickers, preferably two in number, are shown at T to cooperate with the usual leveling cam e' ; said widening pickers and said cam being constructed and arranged substantially as set forth in said Hemphill patent 105 so that no further description thereof is believed necessary except to say that said widening pickers are, at the proper intervals, raised from the positions shown in full lines, Fig. 2, to the dotted position shown therein so as to be moved into the paths 110 of the long butts at opposite ends of the series indicated at A whereby when said series is reciprocated past said widening pickers, two of such butts will be engaged 115 by said pickers and restored to their operative position so as to pass into and be functioned by the knitting cams 14 thereby uniting the loops retained by the withdrawn needles with new loops subsequently formed 120 upon said needles by the restoration thereof 125

130

and the functioning thereby of said knitting cams in the usual well known manner.

In view of the construction of the knitting instruments; or rather in view of the fact that said knitting instruments include independently movable elements, consisting of the yarn drawing element 2 and the sheath element 3, it is desirable that said sheath elements by given positive and independent movements by independent means and for this purpose cams are provided which cooperate with the knitting cams 14 hereinbefore described.

In the present example I have provided 15 a central raising cam 28 disposed directly beneath the cam e^3 and provided with a space 29 between said cams sufficient only to allow the butts 12 and 13 of said sheath elements to pass. The cam 28 is operatively inclined at 20 30, 30 to raise said sheath elements at the proper intervals to cooperate with the yarn drawing elements in the formation of the loops which operations are clearly described and shown in my said patent 1,398,813.

25 As will be seen by referring to Figs. 2 and 5 the sheath member 3 is provided with a block 31 which constitutes a guide for the front side or edge of the yarn drawing element 2 and also forms a support for and 30 a part of the butt 12 or 13 of said sheath elements. Furthermore said block is extended upwardly a predetermined distance to form a stop 32 against which the butt 10 or 11 of its yarn drawing element is 35 adapted to impinge at certain times in the operation of the machine for example when said yarn drawing elements are being depressed by the surfaces w^2 of the stitch cam w . Hence the sheath elements of the knitting instruments will, at times, be depressed by the yarn drawing elements while, at other times as hereinafter stated, said sheaths must be deflected by independent cams herein cams 33 which constitute opposite ends 40 of the cam ring or cylinder M. The cam ring or cylinder M is cut away at 33 along a line herein substantially parallel with the path described by the butts of the sheaths during the depression thereof by the cams 45 w^2 and as indicated in dotted lines in Fig. 2 the inclined surface 33 terminates at a point slightly in advance for the plane passing through the lowermost point in the knitting wave, that is through the lower corner 50 of the cam w and this cam surface 33 unites at said advanced point with the under edge 42 of said cam ring, which under edge constitutes the normal lowermost path of the sheath butts during the knitting operations.

55 After leaving the plane referred to the butts of the yarn drawing elements engage the surface w^3 and are immediately deflected to the upper edge of the cam ring M. At such a time it is desirable to prevent the upward movement of the sheaths of the yarn draw-

ing elements so deflected and it is for this reason that the surface or edge 42 of said cam ring is extended to a point slightly in advance of said plane or to the lowermost point of the inclined surface 33, said surface 70 42 being engaged by the butts of said sheaths and retained thereby in their lower operative path B. Naturally where the yarn drawing element slides within the sheath there will be a tendency, where one of said 75 elements is operated by a cam, for the other element to move therewith and this same tendency exists when the yarn drawing elements are deflected by one or the other of the cams w according to the direction of 80 movement of the needle cylinder and when said yarn drawing elements are being lowered to the stitch forming point of the knitting wave as hereinbefore described. This friction between said elements causes the 85 sheath which, at this time is at the upper level d (see Fig. 2) to start immediately to descend with said yarn drawing element but it will be noted by reference to Fig. 2 that the distance between the upper level d and 90 the lower normal level B is not as great as the distance from the top of the cam e^3 to the casting off point or bottom of the cam w , therefore means are provided for limiting the movement of the sheath so that it will 95 not drop below its normal operating level. For this purpose, therefore, the cam 28 is extended at 43 to form ledges against which the butts of the sheaths will strike, said ledges being disposed directly beneath or 100 transversely of the plane containing the lowermost point of the cam surface w^2 and from this description it will be seen that under ordinary circumstances the block 31 will not be required as a stop to cause the 105 sheath to move with the yarn drawing element as the friction between said elements is sufficient to accomplish this result except when the parts have become so worn that the movement of one will not be sufficient to cause 110 the movement of the other. As in the case of the knitting cams of said Heinphill Patent No. 933,443 the cams of the present machine are made double so as to provide similar operations for the knitting instruments 115 during the opposite or reciprocating movements of the needle carrier and a description of one of said sets of cams will suffice for both. During rotary knitting both the long butts 12 and the short butts 13 of said 120 sheaths are operated by one set only of the cams hereinbefore described. In reciprocating knitting, however, only the sheaths having short butts 13 or about one-half of the knitting instruments remain in operation and at this time the narrowing and widening operations take place. For clearness the short butts 11 and 13 of the yarn drawing and sheath elements are indicated 125 in full lines at their operative levels in Fig. 130

2 it being assumed that the needle carrier is moving in the direction of the arrow *y*. The long butts 10 and 12 of the yarn drawing and sheath elements respectively are, in 5 this figure, shown in their withdrawn positions in full lines and in the dotted lines of said figure the normal paths of the short butts 11 and 13 respectively of the yarn drawing and sheath elements are indicated 10 in connection with the knitting cams. For the purpose of withdrawing the long butt sheath elements preparatory to the narrowing and widening operations a cam 34 herein designated the sheath withdrawing cam 15 is employed. This cam 34 is mounted upon 15 a suitable slide 35 arranged to slide in guides formed in the stand 9 hereinbefore described, whereby said cam 34 may be moved from one position to another or from a position 20 wherein the long sheath butts 12 will pass by the lower edge 36 thereof when travelling along the upper level *d*, without being deflected by said cam, when occupying its other position as shown in Fig. 2 said 25 long butts 12 will be engaged and deflected downwardly to the idle or inoperative level of said sheath members. As in the case of the cam 15, the cam 34 is positioned outside of the cam cylinder *M* so as to engage 30 only the portions of the long butt 12 which project beyond the short butts 13 thus preventing withdrawal of the short butt sheath elements.

Cooperating with the cam 34 is a restoring cam 37 which is disposed in a gap 36 formed in the lower portion *M'* of the ring *M*, and just far enough below the cam 34 to provide a gap 38 through which the butts of the sheath elements will freely pass. The 40 cam 37 is likewise mounted upon a slide 35 so that as said cam 34 is lowered the cam 37 will likewise be lowered and during the raising of said cam 34 said cam 37 will also be raised. The last mentioned movement 45 of said cam 34 effects the restoration of the long butts 12 of the sheath elements which previous to this were travelling along the lower or inoperative level *C* as clearly shown in Fig. 2.

50 From the foregoing description it will be evident that the yarn drawing elements are raised during the withdrawing operations thereof while the sheath elements are lowered and consequently the movements of the 55 two sets of cams 15 and 16, and 37 and 38 must be in opposite directions but it is desirable that they be moved simultaneously in said opposite direction and to accomplish this result I have herein provided an extension 60 39 for the link 26 hereinbefore described which extension has a cam slot 40 formed therein to cooperate with a suitable projection or pin 41 carried by the slide 35 and as said lever 26 is shifted from side to side 65 by the shifting clutch *b*, a vertical recipro-

catory motion will be imparted to the slide 35 thus to raise or lower the cams mounted thereon coincidently with similar movements imparted to the cams 15 and 16 by the bell crank lever 20.

The yarn drawing elements are functioned in substantially the same manner as are the ordinary spring beard or latch needles in a Banner knitting machine and particularly during the narrowing and widening operations thereof, said yarn drawing elements being thrown in and out of operation by widening and narrowing pickers and said instep needles being withdrawn or restored by the instep cams 15 and 16 as described.

The use of the sheath elements however involves additional elements, hence the providing of the additional withdrawing and restoring cams 37 and 38 therefor. When the end needles or knitting instruments of the operative series, during narrowing and widening, are raised by the narrowing pickers in the usual manner the same tendency for the sheath elements to move therewith, due to friction between the two elements, is present. Hence when the first butt of said series is engaged by the right hand picker in Fig. 2 and raised to the level *A*, the sheath thereof would, if it were not for the surface 42 of the cam ring *M*, be carried upwardly therewith to its upper level *d* but owing to the necessity of extending said edge 42 to a point in advance of the vertical plane containing the lowermost corner of said cam *x* naturally the upward movement of the sheath will be retarded at least until said elements have passed beyond the intersection of the surface 33 with the surface 42 but thereafter the sheath will follow said yarn drawing element until the butt thereof strikes the under side of the cam *e*. The sheath then travels along the upper level *d* until its butt engages the opposite cam surface 33 when said sheath will be deflected to its lower normal level with its butt travelling in the groove along the path *B*.

In view of the tendency of one of said loop forming elements to move with the other element when said other element is actuated by its cam, the engagement of the short butt 13 of the sheath element with the cam surface 33 when the yarn drawing element of that particular sheath is in its uppermost or idle position, having been raised thereto by one of the narrowing pickers, said yarn drawing element will be drawn downwardly from said elevated position and unless some means are employed to immediately raise the same, said yarn drawing element will be functioned normally to receive and form a loop whereas the intention is to retain said yarn drawing element at said upper level until the widening pickers have been thrown into operation to restore the same in its natural sequence. For the purpose of returning the

yarn drawing element which has thus been lowered by its sheath, I have herein provided switch cams 44 disposed upon opposite sides of the knitting cams 14 and far enough therefrom so as not to interfere with the operation of the pickers R. These switch cams are shown in their normal positions in full lines, Fig. 2, and have inclined surfaces 45 against which the deflected yarn drawing element butt impinges and is caused to pass upwardly to the idle level A.

With the knitting instruments traveling in the direction of the arrow y the butts of the yarn drawing elements which have been thus deflected will strike against the surface 45 of the left-hand switch cam 44 and be raised thereby to the upper level and when the direction of the needle cylinder is reversed said butts will engage the surface 45 of the switch cam at the right and in like manner be raised to their idle level. It will, however, be seen that the lowermost point of such switch cams project slightly below the path of the butts of the yarn drawing elements passing along the normal knitting level and obviously these points of said cams will be struck by the passing butts and in order that no harm may be done by such contact, said switch cams are pivotally mounted as shown at 46 so as to yield when struck by said butts to permit the passing thereof without deflection. Within the scope and purpose of the invention springs may be applied to said switch cams to cause them to return to their normal positions as indicated in full lines in said figure.

Following the completion of the narrowing operations or at a certain point in the narrowing operations the widening pickers are raised from their full line positions to their dotted line positions hereinbefore described so as to gradually restore the short butt yarn drawing elements which have previously been picked up by the narrowing pickers to their operative positions, and when these widening operations take place the same tendency for the sheath elements to be moved with the yarn drawing elements engaged by said widening pickers will be present and to prevent such movement of said sheath elements at this time a guide cam 47 has been provided to engage the butts of said sheath elements and to restrict, or prevent the downward movements thereof which, unless prevented, would cause the butts of said sheath elements to pass to the lower or idle level C and prevent the normal functioning of said sheath elements coincident with the functioning of their respective yarn drawing elements. In other words should the butts of said restored knitting instruments pass below the cam 28 rather than above as in the normal operation, the loop penetrating member of the sheath will not function to spread the loop and guard the point of the needle hook and in consequence

thereof the loop retained upon the yarn drawing element at this time will fail to be cast off but will, together with the new yarn presented to said yarn drawing element, enter the hook remaining upon the same until a subsequent raising of the cam 37 is effected to restore all of the lowered sheath elements to their normal operating level.

Although I have illustrated in connection with the present invention a yarn drawing instrument similar to that employed in my said Patent 1,398,813, it is clearly within the scope and purpose of the invention to employ any type of knitting instrument where-in yarn drawing sheath elements are provided and require independent or relatively sliding movements to effect the formation of a loop thereby.

While I have herein shown and described merely for illustrative purposes one specific embodiment of my invention, and have disclosed and discussed in detail the construction and arrangement incidental to such disclosure, it is to be distinctly understood that the invention is limited neither to the mere details or relative arrangement of the parts nor to the specific application herein shown, but that extensive variations from the illustrations may be made without departing from the principles thereof.

Claims.

1. Knitting mechanism comprising, in combination, knitting instruments each having two loop forming elements operated independently of each other, means severally to function said elements during the loop forming operations, means separately to withdraw and restore the elements of selected knitting instruments and picker means to operate upon selected remaining instruments.

2. Knitting mechanism comprising, in combination, knitting instruments having cooperating yarn drawing and loop casting off elements, cams severally to function said elements independently of each other during the loop forming operations, simultaneously operated cams separately to withdraw the elements of some of said instruments and means to operate certain of the remaining instruments for narrowing and widening.

3. Knitting mechanism comprising, in combination, a series of knitting instruments having relatively slidably loop forming elements, means severally to function said elements in the formation of loops, means to throw the elements of certain of said instruments out of operation in opposite directions and pick means for picking out of and into operative positions predetermined of said instruments in narrowing and widening.

4. Knitting mechanism comprising, in combination, a series of knitting instruments

- 5 having yarn drawing and loop casting off elements respectively provided with operating butts, cams respectively to engage said butts to function said elements in knitting and other cams respectively to engage the butts of the yarn drawing and loop casting-off elements of certain of said knitting instruments, and remove said elements from operative positions at selected stages in the knitting operation.
6. Knitting mechanism comprising, in combination, a series of knitting instruments having yarn drawing and loop casting off elements respectively provided with operating butts, cams to engage said butts to function said elements in knitting, other cams respectively to engage butts of both elements of certain of said instruments and remove their respective elements from operative position at selected stages in the knitting operation, and picker means for alternately withdrawing and restoring certain of the operative instruments to effect narrowing and widening.
7. Knitting mechanism comprising, in combination, a series of knitting instruments each having relatively movable yarn drawing and sheath elements, a portion of the yarn drawing elements and their sheaths having long butts, the yarn drawing elements and the sheaths of the remaining instruments having relatively short butts, knitting cams respectively to function the yarn drawing elements and sheath elements of all of said instruments to produce knitted fabric and means respectively to withdraw from operative positions the long butt yarn drawing elements and their sheaths.
8. Knitting mechanism comprising, in combination, a series of knitting instruments each having relatively movable yarn drawing and sheath elements, cams respectively to engage the yarn drawing elements and sheaths of all of said instruments to produce knitted fabric, means respectively to withdraw from operative positions the long butt yarn drawing elements and their sheaths and means respectively to restore said long butt yarn drawing elements and their sheaths into operative positions.
9. Knitting mechanism comprising, in combination, a series of knitting instruments each including relatively movable yarn drawing and loop casting off elements, cams respectively to function said elements and cams 15 and 34 respectively to withdraw in opposite directions selected yarn drawing elements and said loop casting off elements from operation.
10. Knitting mechanism comprising, in combination, knitting instruments each including relatively slidable yarn drawing and sheath elements, means to effect independent and joint movements of said elements during knitting, pickers for operating the yarn drawing elements for narrowing and widening and means severally to act upon the sheath elements of the instrument operated by the narrowing picker to restore them to normal position in advance of the yarn drawing element thereof.
11. Knitting mechanism comprising, in combination, a series of knitting instruments each including relatively movable yarn drawing and loop casting off elements, cams respectively to function said elements and cams 15 and 34 respectively to withdraw in opposite directions selected yarn drawing elements and said loop casting off elements from operation.
12. Knitting mechanism comprising, in combination, a series of knitting instruments each including relatively movable yarn drawing and loop casting off elements, cams respectively to function said elements and cams 15 and 34 respectively to simultaneously move selected yarn drawing elements and their loop casting off elements to their respective inoperative positions.
13. Knitting mechanism comprising a series of knitting instruments each including a yarn drawing element and a sheath element, each of said elements having knitting butts, means to engage said butts to function said elements in knitting, pick means to act upon the butts of the yarn drawing elements of selected instruments in narrowing and widening, and a guard 47 to engage the butts of the sheath elements to restrict movements of the sheath elements of the yarn drawing elements that are actuated by the widening picks.
14. Knitting mechanism comprising, in combination, knitting instruments each including relatively slidable yarn drawing and sheath elements, means including butts on said elements to effect independent and joint movements of said elements during knitting, pickers for operating upon the butts of the yarn drawing elements for narrowing and

widening and means including cams 33 and 45 to act upon the butts of the elements of the instruments following the movement thereof by a narrowing picker to complete the placing of said elements in their inoperative positions.

15. In a knitting machine, a needle consisting of a hook member and a separate latch member reciprocable to effect the required projecting and casting off movements and movable relatively to effect the cooperation of the hook and latch, means to give an abnormal projecting movement to the hook member to throw the needle out of action, and means to move said latch member in a reverse direction.

16. In a knitting machine, a needle consisting of a hook member and a separate latch member reciprocable to effect the required projecting and casting-off movements and movable relatively to effect the cooperation of the hook and latch, means to give an abnormal projecting movement to the hook member to throw the needle out of action, and means to effect the movement of said latch member simultaneously with the abnormal projection of said hook in an opposite direction to that of said hook to withdraw said latch member to its idle position.

17. In a knitting mechanism, a series of needles each consisting of relatively reciprocable hook and latch members, means to function the needle members in knitting, means respectively to engage the hook and latch members of some of said needles and move them to inoperative positions and picker means to move a selected

number of the hook members only of the active needles from and to their operative positions to narrow and widen. 40

18. In a knitting mechanism, a series of needles each consisting of relatively reciprocable hook and latch members, means to function the needle members in knitting, means respectively to engage the hook and latch members of some of said needles and move them to inoperative positions, picker means to move the hook members of a selected number of active needles from and to their operative positions to narrow and widen and means to control the movements of the latch members of said narrowing and widening needles during the picking up and down of their hook members. 45 50

19. In a knitting mechanism a series of needles each consisting of relatively reciprocable hook and latch members, means to function the needle members in knitting, means respectively to engage the hook and latch members of some of said needles and move them to inoperative positions, pickers to move the hook members of a selected number of leading needles to their inoperative positions to narrow, means to depress the latch members of said narrowing needles, pickers to restore certain narrowing needles to knitting level for widening and means to prevent conjoint movement of the latch members of said certain needles during the restoration of their hook members. 55 60 65 70

In testimony whereof, I have signed my name to this specification.

SYDNEY E. TAFT.
